ILLUMINABLE WREATH

Emidio Di Rico, East Elmhurst, N.Y., assignor to Raylite Electric Corporation, Bronx, N.Y., a corporation of New York

Filed Oct. 5, 1965, Ser. No. 87,319

Term of patent 14 years

(Cl. D29—1)

Fig. 1.

FIG. 1 is a front elevational view of an illuminable wreath showing my new design, and

FIG. 2 is a sectional view thereof taken substantially along line 2—2 in FIG. 1.

The back of the wreath is convex as indicated by the sectional view of FIG. 2.

I claim:

The ornamental design for an illuminable wreath, as shown and described.
